UNITED STATES PATENT OFFICE.

ROBERT S. DAVIS, OF POWHATAN, LOUISIANA.

ADJUSTABLE STANDARD AND HEEL-KNIFE.

1,347,257.

Specification of Letters Patent. Patented July 20, 1920.

Application filed September 19, 1919. Serial No. 324,894.

To all whom it may concern:

Be it known that I, ROBERT S. DAVIS, a citizen of the United States, residing at Powhatan, in the parish of Natchitoches, 5 State of Louisiana, have invented a new and useful Adjustable Standard and Heel-Knife; and I do hereby declare the following to be a full, clear, and exact description of the invention, such as will enable others skilled in the art to which it appertains to 10 make and use the same.

The invention relates to plows and has for its object to provide means whereby the standard and the heel knife may be easily 15 and quickly adjusted so that the point of the plow may be raised or lowered thereby adjusting said plow in accordance with the draft hitch so that the plow will take or throw a deeper furrow or a shallow one according to the desire of the operator.

A further object is to provide a standard arching the plow beam, the upper end of said standard being provided with means whereby said end may be moved forwardly 25 or rearwardly to lower or raise the plow point and to provide a heel knife pivoted to the standard and connected to the adjusting means for the upper end of the standard whereby the heel knife and the standard may 30 be adjusted simultaneously.

With the above and other objects in view the invention resides in the combination and arrangement of parts as hereinafter set forth, shown in the drawings, described and 35 claimed, it being understood that changes in the precise embodiment of the invention may be made within the scope of what is claimed without departing from the spirit of the invention.

40 In the drawings:—

Figure 1 is a side elevation of a portion of a plow beam showing the adjustable standard and heel knife applied thereto.

Fig. 2 is a top plan view of the adjustable 45 standard and heel knife mechanism.

Fig. 3 is a vertical sectional view taken on line 3—3 of Fig. 1.

Fig. 4 is a vertical sectional view taken on line 4—4 of Fig. 1.

50 Referring to the drawing, the numeral 1 designates a plow beam and 2 the standard, which standard is formed from two plates 3, which have their upper ends engaging the outer faces of the plow beam 1 and extending 55 above said plow beam. Plates 3 which form the standard are held in spaced rela-

tion from each other by sleeves 4 disposed between said plates and through which sleeves and the plates, bolts 5 pass. Sleeves 4 are spaced above and below the plow beam 60 1 and are slightly spaced from the same to allow forward and rearward movement of the upper end of the standard during an adjusting operation. A conventional form of plow 6 may be secured in any suitable 65 manner to the standard and the adjusting mechanism being particularly adapted to raise or lower the plow point 7.

The standard is pivotally mounted on a bolt 8, which passes transversely through the 70 plate 3 and through the end 9 of a rearwardly and upwardly extending brace 10, the upper end of said brace being secured as at 11 to the under face of the plow beam 1 by means of a vertically disposed bolt 12. 75 Standard 2 is adapted to pivot on the bolt 8, thereby pivoting on a fixed point. Also pivotally mounted on the bolt 8 are downwardly and rearwardly extending bars 13 between which bars a heel knife 14 is 80 securely held by means of bolts 15, which pass transversely through the bars 13 and the heel knife 14. The bars 13 and the heel knife also have secured thereto by means of a bolt 17 upwardly extending arms 18, the upper 85 ends of said arms being pivotally secured as at 19 to a U-shaped arching plate 20, which arches the rearwardly and upwardly extending brace 10 and is adapted to have threaded into its upper end as at 21 the lower end 22 90 of a vertically disposed operating screw 23 which screw is loosely mounted in a vertically disposed aperture 24 which passes through the plow beam and through an aperture 25 in a lug 26, there being a nut 27 95 disposed between the lug 26 in the upper face of the plow beam thereby forming means whereby the threaded shaft 23 will move upwardly and downwardly when the wheel 28 is rotated. When the wheel 28 is rotated 100 the square portion 29 of the vertical shaft 23 slides through a square aperture 30 in a bevel gear 31, the aperture 30 being of a size which will allow the square portion 29 to freely slide through the same. The lower 105 end 22 of the vertical shaft 23 being threaded into the U-shaped member 20, it will be seen that the heel knife will incline forwardly or rearwardly according to the direction of turn of the wheel 28. It will also be seen 110 that by pivoting the U-shaped arching plate 20 as at 19 that said U-shaped plate will

accommodate the slight movement to one side or the other of the vertical center line of the threaded shaft 23 of the heel knife when said heel knife is moved upwardly or downwardly. During the rotation of the bevel gear 31 which is in mesh with the bevel gear 32 secured to the end of a threaded shaft 33 which is rotatably mounted in bearings 34 of brackets 35 carried by the upper 5 face of the plow beam, it will be seen that the upper end 36 of the standard will be moved rearwardly as the heel knife is raised therefore, as the plow point is raised to adjust the plow point so that it will take proper furrow the heel knife is accordingly 10 adjusted. Threaded shaft 33 passes through and is threaded in a rockable bearing 37 which has its pintles 38 in elongated bearings 39 in the upper ends of the plates 3. 15 When the adjusting mechanism is revolved so as to lower the plow point 7 or flatten the plow, it will be seen that it will be possible by the same adjustment to properly 20 adjust the heel knife. 25 From the above it will be seen that an adjusting means has been provided for standards and heel knives wherein by the single operation both members are adjusted and also the mechanism wherein the complicated, slow and laborious use of wrenches 30 is eliminated.

The invention having been set forth what is claimed as new and useful is:

1. An adjustable standard and heel knife comprising a heel knife carrying member carried by a plow beam, said knife carrying member being disposed below the plow beam, the lower end of the standard and the forward end of the knife carrying member 35 being pivoted to each other, the standard comprising two members held in spaced relation to each other and having their upper ends arching the plow beam, a bracket carried on the upper face of the plow beam and 40 having rotatably mounted in bearings thereof a threaded shaft, said threaded shaft passing through a pivoted trunnion block having bearings in the upper end of the standard, a gear carried by said threaded shaft, 45 said gear meshing with a gear carried by a

vertically disposed threaded shaft, the lower end of said vertically disposed threaded shaft being threaded in a member pivotally secured to the knife carrying member, the gear carried by the vertically disposed 55 threaded shaft being rotatable with said shaft but slideable thereon, and means whereby said vertically disposed threaded shaft may be rotated to raise and lower the plow point and simultaneously adjust the heel 60 knife carrying member.

2. An adjustable standard and heel knife comprising a knife carrying member carried by a plow beam, said knife carrying member being disposed below the plow beam, the lower end of the standard and the forward end of the knife carrying member being pivoted on a common pivotal point, said pivotal point being in an upwardly and rearwardly extending brace carried by the 70 plow beam, the standard comprising two members held in spaced relation to each other and having their upper end arching the plow beam, a bracket carried on the upper face of the plow beam and having 75 rotatably mounted in bearings thereof a threaded shaft, the rear end of said threaded shaft having secured thereto a gear, said gear meshing with a bevel gear slidably mounted on a vertically disposed threaded 80 shaft but rotatable with said shaft, the first mentioned threaded shaft passing through a pivoted trunnion pivoted in bearings of the upper end of the side plates of the standard, the vertically disposed threaded shaft being 85 threaded through a member carried by the plow beam and having its lower end threaded into a pivoted member, said pivoted member being pivotally secured to heel knife carrying member and means whereby 90 said vertically disposed threaded shaft may be rotated for simultaneously inclining the plow point and heel knife carrying member.

In testimony whereof I have signed my name to this specification in the presence of 95 two subscribing witnesses.

ROBERT S. DAVIS.
